Edward C. Glafke, Kentfield, Calif., assignor to Service
Men's Trophies, Inc., Richmond, Calif., a corporation
of California

Application August 24, 1953, Serial No. 26,566

Term of patent 7 years

(Cl. D29—28)

To all whom it may concern:

Be it known that I, Edward C. Glafke, a citizen of the United States and a resident of Kentfield, county of Marin, California, have invented a new, original, and ornamental Design for a Trophy, of which the following is a specification, reference being had to the accompanying drawing, forming a part thereof.

Figure 1 is a front perspective view of a trophy showing my new design;

Figure 2 is a side elevational view thereof with portions broken away for convenience of illustration only; and

Figure 3 is a rear elevational view thereof with portions broken away for convenience of illustration only.

The dominant characteristics of my design are indicated by the solid line representations in the drawing.

I claim:

The ornamental design for a trophy, substantially as shown and described.
